[57] **CLAIM**

The ornamental design for a combined digital audio disc
player, radio and tape recorder, shown and described.

DESCRIPTION

FIG. 1 is a top and front perspective view of a
combined digital audio disc player, radio and tape recorder
showing my new design, with the disc and tape com-
partment doors open and the left speaker separated;
FIG. 2 is a front elevational view thereof;
FIG. 3 is a rear elevational view thereof;
FIG. 4 is a top plan view thereof;
FIG. 5 is a bottom plan view thereof;
FIG. 6 is a right side elevational view thereof; and
FIG. 7 is a left side elevational view thereof.
